UNITED STATES PATENT OFFICE.

JOHN A. CASHEL, OF WORTHINGTON, MINNESOTA.

INTEREST-COMPUTING MACHINE.

1,084,254.

Specification of Letters Patent.

Patented Jan. 13, 1914.

Application filed May 2, 1912. Serial No. 694,613.

To all whom it may concern:

Be it known that I, JOHN A. CASHEL, a citizen of the United States, residing at Worthington, in the county of Nobles and 5 State of Minnesota, have invented certain new and useful Improvements in Interest-Computing Machines, of which the following is a specification.

My invention relates to computing machines, and particularly to those which are 10 used in the calculation or computation of interest, annuities, etc.

The main object of my invention is to 15 provide a computing machine of simple construction, by which interest upon different amounts at different rates may be quickly and accurately determined.

A further object of the invention is to 20 provide a machine of this character in which a plurality of sets of related calculating tables are so arranged as to permit of adjustment within a suitable casing or carrier to a position where they may be exposed to view, so that the operator may 25 move to proper position the table which he desires to use, while the others remain concealed in order to prevent confusion.

The nature and scope of my invention 30 will be more fully understood from the following description, taken in connection with the accompanying drawings, in which—

Figure 1 is a front elevation of a computing machine embodying my invention; Fig. 2 is an end elevation of the same; Fig. 3 is a vertical section on the line 3—3 of 35 Fig. 1; Fig. 4 is a fragmentary sectional view of the right hand portion of the machine, showing the manner of mounting the interest rolls and the mechanism for rotating them; Fig. 5 is a detail sectional view 40 of the time indicator shown at the left-hand side of Fig. 1; Fig. 6 is an enlarged perspective view of one of the finders; and Fig. 7 is a side elevation of one of the interest-table rolls.

My interest-computing machine comprises a plurality of interest table prisms or cylinders 1, having pivot pins 2, upon either end journaled in disks 4, carried by a central shaft 5, which is journaled in the end walls of a casing 6. One end of the shaft is provided with a hand-wheel 7, by which the disks may be rotated, and the pivot-pins 50 55 2 carry pinions 9, which intermesh, so that a gear-wheel 12, normally spring-pressed outwardly, may be pushed into mesh with

any adjacent pinion when the entire series of prisms may be rotated axially by means of the thumb-piece 14. The prisms or cylinders 1, thus have a planetary movement,— 60 that is to say, each is rotatable upon its own axis and bodily around the common central axis.

There are preferably thirty-one prisms, one for each day of the month, and each prism is provided with a plurality of faces carrying respectively series of figures indicating the interest for a certain number of days for varying amounts. In Fig. 7, I have shown three faces of a hexagonal prism 65 showing the interest for twenty-five days at 4, 5, and 6 per cent., respectively, upon amounts ranging from one hundred to nine hundred dollars. If desired, the rate per day for each amount may also be indicated 70 in each space. 75

Above the skeleton day-cylinder above described, I may provide a corresponding skeleton cylinder having twelve interest-bearing prisms for the different months. 80 The manner of mounting and operating these prisms is exactly similar to that previously described in regard to the day cylinder, and I have indicated the corresponding parts by the same reference numerals 85 primed. A third multiple-prism cylinder to indicate the interest for a series of years may be placed above the monthly cylinder if desired.

The method of operating the portion of 90 my machine above described for the purpose of determining the interest for any amount will now be understood.

To find the amount for any number of days, the skeleton cylinder is first turned by 95 means of the hand-wheel 7, until the proper day-prism is in alinement with the sight-slot 15, extending across the front of the casing, which is indicated by the pointer 17, standing opposite the corresponding 100 numeral on the face of the hand-wheel 7. The cylinder is held in any set position by the dog 37, which rides over the toothed locking wheel 36. The thumb-knob 14 is then pushed inwardly until the spur-gear 12 is 105 in mesh with the adjacent pinion 9, after which the series of prisms may be rotated in unison about their axes, until the face bearing the series of interest computations for the desired rate per cent. is opposite 110 the sight-slot. Extending longitudinally of the slot is a series of numbers, from one hun-

dred to nine hundred, which indicate the principal amounts corresponding with the adjacent interest computations. If desired, an indicator 20, having a magnifying lens 21, shown in detail in Fig. 6, may be mounted upon a guide-rod 23, and adapted to be slid over the figures which are to be read. To further facilitate the rapid calculation of interest between certain dates, I provide 10 a coöperating set of disks bearing upon their peripheries numbers corresponding respectively to the number of days in a year and to the number of months, with subdivisions for the days of each month. These two 15 disks 25, 26, are mounted upon the axle 28, the former loose thereon and the latter splined thereto. The loose disk 25 carries upon its periphery the 365 subdivisions, and is normally in zero position, being 20 turned after each operation by means of a torsional spring 29.

The complete operation of my machine will be clear from the foregoing description.

Let it be desired to determine the interest 25 upon five hundred dollars at five per cent., from March 14th until April 8th. The disk 26 is first rotated by means of the thumb-knob 30, until the date March 14th appears in the sight-slot or window 32; then, by 30 pressing inwardly upon the knob, the notches or serrations 33, upon the adjacent edges of the disks 25 and 26, are engaged. Now upon turning the locked disks until the date April 8th, appears behind window 32, 35 the numeral 25, indicating the number of days between the two dates, will appear at the window upon the disk 25. As soon as pressure upon the knob 30 is released, the spring-operated disk 25 will be disengaged 40 from the disk 26 and will return to zero position, suitable stops 34, being provided to limit the movement. Having thus determined the number of days between the required dates, the main skeleton cylinder is 45 rotated by means of the wheel 7, until the 25th day prism is opposite the sight-slot 15. After rotating the prisms upon their axes by means of the gear 12, as previously described, until the 5 per cent. face is visible 50 in the slot 15, the indicator 20 is slid along the rod 23 until it is opposite the sum 500 and the adjacent interest amount may then be read directly as \$1.74. These manipulations can be made very rapidly, and the simplicity of the machine will be appreciated 55

by bankers and others who are required to determine quickly and in rapid succession the interest between certain dates upon varying amounts at different rates.

I have described in detail the specific construction illustrated in the accompanying drawings, for the purpose of disclosing an embodiment of my invention, but I am aware that various changes may be made therein without departing from the scope 60 of my claims or the spirit of my invention. 65

I claim:—

1. In an interest-computing machine, comprising a revoluble disk having upon its periphery a series of numerals arranged in 70 arithmetical progression from unity upward, a spring normally causing said disk to assume a zero position when unrestrained, a second revoluble disk coaxial with said first disk and having upon its periphery successive series of numerals indicating the days 75 of each month, means for rotating said second disk independently of the first-named disk, means for permitting one disk to be moved toward the other disk, and means for 80 causing a locking engagement therebetween, said spring operating to release said engagement when the parts are unrestrained, thereby permitting the first-named disk to return to zero position. 85

2. An interest-computing machine comprising a casing having a sight-slot therein, a revoluble frame journaled in said casing, an annular series of revoluble cylinders journaled in said frame and provided with intermeshing pinions, each of said cylinders having inscribed thereon a plurality of series of numerals indicating amounts of interest on sums varying progressively, each series being at a different rate, and the interest 90 amounts upon adjacent cylinders differing by a unit period of time, and a spur-gear slidably mounted in the casing and normally out of engagement with said pinions, but adapted to be moved into mesh 95 with any adjacent pinion of the series, whereby the desired series of numbers may be brought beneath said sight-slot. 100

In testimony whereof I affix my signature in presence of two witnesses.

JOHN A. CASHEL.
